UNITED STATES PATENT OFFICE.

JOSEPH ASA SHELTON, OF HENDERSON, KENTUCKY.

TROLLEY CONSTRUCTION FOR BARBERS' ELECTRICAL EQUIPMENT.

1,374,117.

Specification of Letters Patent.

Patented Apr. 5, 1921.

Application filed August 14, 1919. Serial No. 317,462.

To all whom it may concern:

Be it known that I, JOSEPH ASA SHELTON, a citizen of the United States, residing at Henderson, in the county of Henderson and State of Kentucky, have invented a new and useful Trolley Construction for Barbers' Electrical Equipment, of which the following is a specification.

This invention has reference to trolley construction for barbers' electrical equipment, and its object is to provide means whereby electrical current may be supplied to any one of numerous chairs or stations in a barber shop without the necessity of uncoupling and recoupling the equipment every time that its service is needed.

In accordance with the invention, current is fed through two superposed overhead conductors at a suitable height to be out of the way and the conductors support a carriage capable of traveling thereon along a line of barbers' chairs. The carriage is arranged to support such mechanism as is usually employed in electrically driven barbers' equipment with the latter in pendent relation to the carriage so that as occasion requires the equipment may be moved to the desired chair ready for use without any plugging in, which latter operation is the customary practice.

The invention will be best understood from a consideration of the following detailed description taken in connection with the accompanying drawing forming part of this specification, with the understanding, however, that the invention is not confined to any strict conformity with the showing of the drawing, but may be changed and modified so long as such changes and modifications mark no material departure from the salient features of the invention as expressed in the appended claims.

In the drawing:

Figure 1 is an elevation of the trolley structure as viewed from one face.

Fig. 2 is an elevation of the same structure as viewed from the opposite face.

Fig. 3 is a plan view of the structure shown in Figs. 1 and 2.

Fig. 4 is a section on the line 4—4 of Fig. 1.

Referring to the drawing, there are shown two conductors 1, 2, which may be considered as bare conductors arranged at a suitable height and in substantially parallel relation and as connected with a suit-

able source of current. The conductors 1 and 2 are to be understood as extended along a line of barber chairs in a barber shop. Adapted to run along the track formed by the two conductors 1 and 2 is a body member 3 which may be of elongated conformation and so arranged as to span the distance between the two conductors 1 and 2 and at the same time extend lengthwise of the track. The body member 3 is or may be made of some suitable insulating material. Wood will answer for the body member 3 if the voltage of the current employed be sufficiently low, or the body member 3 may be made of hard rubber or fiber, or insulation may be employed wherever found desirable.

Near opposite ends of the body member 3 trolley wheels 4 and 5 are mounted. Each wheel, which may be of good conducting material such as brass, is mounted on a spindle or arbor 6 traversing the body 3 and held by a nut 7. Each roller 4 and 5 is provided with a peripheral groove 8 to run upon a respective conductor 1 or 2 as the case may be. Carried by the body member 3 adjacent to each roller 4 and 5 is another roller 9, which may be of insulating material, and each roller 9 is mounted on an arbor or spindle 10 traversing the block 3 and held in place by a nut 11. The roller 9 is so situated as to underrun a respective conductor 1 or 2 as the case may be, and prevent escape of the roller 4 or 5 from the trolley wire 1 or 2. Adjacent to the meeting parts of a wheel 4 or 5 and the roller 9 associated therewith, is an eye or guide 12 on the body member 3.

One face of the body member 3 has a groove 13 formed therein, the groove being so situated as to extend up and down when the body 3 is properly located on the track formed by the two conductors or trolley wires 1 and 2. Seated in the groove 13 is a tube 14 serving as a support for barbers' electrical equipment of any suitable character, which equipment is therefore not shown for it may be of well known construction. The tube 14 also serves as a conduit for electrical conductors 15 which may be suitably insulated conductors each connected to a respective arbor 6 of the wheels 4 and 5, the conductors 15 being held to the arbors by the nuts 7. To retain the tube 14 in position on the body member 3 there is provided a clamping strap 16 made fast to the

body member 3 by bolts 17 having wing nuts 18 for ready manipulation so that if it be desirable at any time to change the equipment such change may be performed 5 without the necessity of skilled labor.

In barber shops as usually equipped with electrical apparatus for use at the barber chairs, it is necessary to move the equipment from some point of storage in the shop 10 to the chair whenever it is desired to put the equipment into service. This means the transportation of the equipment across the shop to the chair and the plugging-in of the electrical side of the apparatus to an 15 electrical socket usually located in an electrolier. This is an awkward and more or less time-consuming operation and the equipment, when in use, is often in the way of other persons than the one using it.

20 By the invention the equipment is always out of the way and may be moved from chair to chair without interference with other workers, and occupies no floor space, nor does it require the attachment to and 25 disconnection of a plug from the source of current.

By making the conductors 1 and 2 sufficiently stiff or taut the carriage is maintained in its upright position despite the 30 weight of the electrical equipment depending therefrom to one side of the carriage, and the trolley may be operated without material side swing.

What is claimed is:—

35 1. In a trolley construction, superposed spaced electric conductors together constituting a track, and a carriage mounted on the conductors and comprising a rigid body member disposed diagonally of the conductors with grooved trolley wheels at opposite ends, each wheel being above and engaging a respective one of the conductors and each grooved wheel having a retaining wheel associated therewith in underlying 40 relation to the respective conductor.

50 2. In a trolley construction, superposed spaced electric conductors together constituting a track, and a carriage mounted on the conductors and comprising a rigid body member disposed diagonally of the conductors with grooved trolley wheels at opposite ends, each wheel being above and engaging a respective one of the conductors and each grooved wheel having a retaining 55 wheel associated therewith in underlying relation to the respective conductor, said body member having an upright tubular guide for electrical conductors situated on the side of the body member remote from the trolley wheels.

60 3. In a trolley construction, superposed spaced electric conductors constituting a track, and a carriage mounted on the conductors and comprising a rigid body member disposed diagonally of the conductors

with grooved trolley wheels at opposite ends, each wheel being above and engaging a respective one of the conductors and each grooved wheel having a retaining wheel associated therewith in underlying relation to the respective conductor, said body member having an upright tubular guide for electrical conductors situated on the side of the body member remote from the trolley wheels, and a readily removable clamp for holding the tubular member to the body member. 75

4. In a trolley construction, superposed spaced electric conductors together constituting a track, and a carriage mounted on the conductors and comprising a rigid body member disposed diagonally of the conductors with grooved trolley wheels at opposite ends, each wheel being above and engaging a respective one of the conductors and each grooved wheel having a retaining wheel associated therewith in underlying relation to the respective conductor, said body member being provided with guides on the face thereof carrying the trolley wheels and closely adjacent to said trolley wheels. 85

5. In a trolley construction, superposed spaced electric conductors together constituting a track, and a rigid body member arranged diagonally of the track and provided with trolley wheels at opposite ends with one wheel running on the upper conductor, and the other wheel running on the lower conductor, other wheels individual to the first-named wheels to confine the wheels to the respective conductors and located in 95 underriding relation thereto, and means carried by the body member in pendent relation to said body member for carrying electrical equipment connected to the feeding conductors. 100

6. In a trolley construction, superposed spaced electric conductors together constituting a track, and a rigid body member arranged diagonally of the track and provided with trolley wheels at opposite ends with one wheel running on the upper conductor, and the other wheel running on the lower conductor, other wheels individual to the first-named wheels to confine the wheels to the respective conductors and located in 115 underriding relation thereto, and means carried by the body member in pendent relation to said body member for carrying electrical equipment connected to the feeding conductors, said carrying means for electrical equipment comprising a tube clamped to and carried by the body member and serving as an inclosure for feeding conductors connected to the trolley wheels. 120

7. In a trolley construction for barbers' 125 electrical equipment, superposed spaced conductors constituting a track, a carriage comprising a rigid elongated body member extending from one conductor to the other and also lengthwise of the conductor to one 130

side thereof, grooved rollers mounted on the body member on the face thereof toward the conductors, and running on respective ones of the conductors with one roller in advance of the other roller, other rollers mounted on the body member underneath the first-named rollers and respective ones of the conductors to hold the latter in the grooves of the rollers against escape therefrom, a substantially upright tube carried by the body member between the ends thereof, and on the face of the body member remote from

the conductors, and electrical conductors extending through the tube and electrically connected, respectively, to the grooved 15 trolley wheels.

In testimony that I claim the foregoing as my own, I have hereto affixed my signature.

JOSEPH ASA SHELTON.
